WELL FLUID CONTROLLING DEVICE

Jeddy D. Nixon, Houston, Tex., assignor of one-half to Wilson Supply Company, Houston, Tex., a corporation of Texas

Application March 4, 1940, Serial No. 322,065

21 Claims. (Cl. 103—234)

This invention relates to new and useful improvements in well fluid controlling devices.

This application involves certain improvements upon the apparatus set forth in my co-pending application, Serial No. 304,684, filed November 16, 1939, and is filed as a continuation in part of my co-pending application, Serial No. 317,073, filed February 2, 1940.

One object of the invention is to provide an improved well flowing device including a spring impelled valve operating member arranged to be held out of valve operating position by a weight bar, whereby said member is released when the bar is lifted and automatically actuates the valve to admit lifting fluid.

Another object of the invention is to provide improved means for controlling the admission of a lifting fluid under pressure to a well pipe to lift the well fluid therein; whether the source of lifting fluid is from the well proper or from a supply outside of the well.

An important object of the invention is to provide an improved well flowing device having a lifting fluid inlet and closure means therefor, together with means for normally holding the closure means open and operable from the surface of the well to release said closure means, whereby the lifting fluid will actuate said closure means and shut off the admission of lifting fluid.

An important object of the invention is to provide an improved fluid flow control means suitable for low fluid type of wells which is operated from the well surface and so constructed that the well fluid may be produced from any point at the bottom of the well which is necessary to lift said well fluid in accordance with its flow into said well, whereby a low fluid type of well may be readily and economically produced.

A further object of the invention is to provide improved means for releasing trapped lifting fluid when the operating member is depressed to permit the inlet valve to close; said means being arranged to close when the inlet valve is opened.

Still another object of the invention is to provide means for shielding the weight bar, whereby it cannot be unintentionally displaced by upwardly flowing fluids in the well.

An important object of the invention is to provide a pressure fluid inlet valve and actuating means therefor together with a pressure fluid conductor surrounded by a well fluid conductor and coupled to a pressure fluid conducting tubing having therein a well fluid elevating pipe connected with the well fluid conductor, whereby

pressure fluid may be discharged on top of the column of well fluid standing in the conducting tubing for displacing and elevating said well fluid in said pipe and discharging into said well fluid conductor below said valve for elevation through said valve to the tubing; the advantage of such an arrangement being that substantially all of the well fluid below said valve in said conducting tubing and said elevating pipe is lifted and expelled therefrom, whereby a greater and more efficient recovery is had.

The contacting of the upwardly flowing column of well and pressure fluid on an actuating member for the fluid flow control means would be objectionable because, due to the skin friction of the moving column of fluid on the actuating member, there would be a tendency for said member to be lifted out of its operating position, which would tend to give a bouncing action to said member and a moderately rapid opening and closing of said control means.

Still another object of the invention is to provide improved means upon said fluid flow control means for housing the actuating member to keep the operating pressure fluid from beneath said actuating member and the upward flow of fluid through said control means from contacting said member, whereby the operation of said control means and said actuating member is positive and is not interfered with when said control means is in an open position.

A further object of the invention is to provide fluid flow control means so constructed that the pressure fluid is introduced upon a large surface of the well fluid in a well fluid accumulating chamber to displace and force said well fluid up the flow or delivery pipe, whereby a greater quantity of well fluid will be produced with less volume of pressure fluid and the full force of said pressure fluid is exerted upon said well fluid with less slippage or channelling of said pressure fluid through said well fluid.

A construction designed to carry out the invention will be hereinafter described, together with other features and objects of the invention.

The invention will be more readily understood from the following specification and by reference to the accompanying drawings, in which an example of the invention is shown, and wherein:

Figure 1 is a view partly in section and partly in elevation of the upper portion of a well;

Figure 2 is a continuation of Figure 1, showing the middle portion of a well, and a valve constructed in accordance with the invention, mounted therein;

Figure 3 is a continuation of Figure 2, showing the lower portion of the well;

Figure 4 is an enlarged detailed view, showing the upper portion of the flow device in an open position;

Figure 5 is a continuation of Figure 4, showing the lower portion of said device;

Figure 6 is a detailed view of the upper portion of the flow device, showing its closed position;

Figure 7 is a horizontal, cross-sectional view taken on the line 7-7 of Figure 5;

Figure 8 is a similar view taken on the line 8-8 of Figure 6;

Figure 9 is an enlarged detailed view of the upper portion of a modified form of the flow device, showing the same in its open position;

Figure 10 is a continuation of Figure 9, showing the lower portion of said device;

Figure 11 is a horizontal, cross-sectional view taken on the line 11-11 of Figure 10;

Figure 12 is a detailed view, showing the flow device in its closed position;

Figure 13 is a horizontal, cross-sectional view taken on the line 13-13 of Figure 9; and

Figure 14 is a diagrammatic view, showing how one group of ball valves is opened ahead of the other group.

In the drawings, the numeral 20 designates the usual well casing (Figures 1, 2 and 3) which has a well tubing string 21 depending axially therethrough. The upper end of the casing is screwed into the usual casing head 22, mounted above the ground level, and the upper end of the tubing string is supported within the casing head in the regular manner. All of the above-ground structure may be substantially the same as that set forth in any of my above-mentioned patents and co-pending applications, although such structure has not been shown and forms no part of the present invention.

The tubing string may extend substantially the full length of the casing 20, and its lower end may terminate within the lower portion of said casing or it may extend below said casing to within a short distance of the bottom of the well at some distance below the lower end of said casing. A suitable liner 23, either perforated or plain, may be provided on the lower end of said casing, or the lower portion of the well bore below said casing may be open or uncased. The lower end of said tubing 21 may terminate within said casing, or in said liner, or in said uncased portion of said well bore, or below said liner; and preferably a suitable screen or bull plug 24 is provided on the lower end of said tubing string. The usual standing or foot valve 25 is mounted within the lower end of said tubing above the bull plug 24.

The tubing string 21 is preferably provided with a number of flow or kick-off valves 26 intermediate its ends and in spaced relation to the standing fluid level of the well, as pointed out in my above-mentioned patents and co-pending applications. The construction of these flow valves may be the same as that taught in my Patent No. 2,171,480, or any other structure suitable for the purpose. These valves serve to lower the well fluid level in said casing 20 and said well tubing 21 down to the point or level at which it is desired to operate or produce the well. In some instances one of or substantially the same flow valve is used as a producing or operating valve, but in some wells where it becomes necessary to produce said well fluid at a point below the end

of said casing string 20, or in the liner 23 mounted in the lower end of said casing, or below a perforated portion of said casing string or of said liner; and when such a condition occurs the usual kick-off valve 26 may not be used at this point. Therefore, it is necessary to set a packer 27, preferably of my own construction such as is shown in my Patent No. 2,171,479, although any desired packer or other seal-off device may be used. It is preferred to mount the packer 27 in said tubing string and to set said packer as low in said casing string as is possible, in accordance with the position of said liner 23 or of the above-mentioned perforations (not shown).

An elongate, cylindrical valve 28 is mounted in said tubing string just above said packer 27 and while at first glance this valve seems to differ somewhat from my usual kick-off valve, its basic principle of action is the same. The upper end of said valve 28 is provided with a cylindrical collar or cap 29 having an internally screw-threaded box 30 on its upper end for receiving a depending, externally screw-threaded pin 31 of said tubing string 21 for connecting the upper end of said valve into said tubing. The lower end of said cap 29 is provided with a box 32 similar to said box 30 for engaging an upstanding, externally screw-threaded pin 33 on the upper end of an upper valve body or head 34. The lower portion of this body is provided with external screw-threads 35 for receiving an internally screw-threaded box 36 upon the upper end of an elongated, cylindrical sleeve 37 and this sleeve has a similar threaded box 38 on its lower end for receiving one end of an externally screw-threaded lower valve body or cross plug 39. A cylindrical collar 40 similar to the collar 29 is threaded onto the lower portion of said lower valve body 39 and has an internally screw-threaded box 41 on its lower end for receiving the threaded pin 42 of said tubing 21 to connect the lower portion of said tubing to said valve 28. A relatively soft metal packing ring 43 is inserted between the upper end of said upper valve body 34 and the lower end of said collar 29, and between the lower end of said body and the upper end of said sleeve 37, and between the lower end of said sleeve and the upper end of said collar 40 for sealing these joints and connections for preventing leakage at said connections. Thus, it will be seen that said valve 28 may be readily connected in said tubing string.

The upper valve body or head 34 is provided with an internal, cylindrical chamber 44. A plurality of radial, internally screw-threaded ports 45 extend outwardly through the walls of said valve body and provide communication between the annular space within said casing 20 and said tubing string 21 through said chamber 44. When said ports are opened (Figures 5 and 9), pressure fluid may enter said tubing from said annular space of said casing. It is preferred to locate said ports in an equi-distantly, spaced relation around said chamber and all in the same horizontal plane. However, while this valve has been shown and described with three ports, one or more ports may be used and arranged as desired. In some instances where a greater number of ports are provided, said body 34 will be elongated and the ports formed in groups of one to four ports each and each group would preferably be on a horizontal plane.

Each port 45 is provided with a valve cage or insert unit 46 threaded thereinto and having a co-axial passageway 47 extending through each valve cage. The inner end of each passageway

47 is formed with a ground, tapered seat 48, so that a ball valve 49 may be mounted in the passageway of each valve cage 46, for engaging the seat 48 and closing said passageway, whereby each of said ports will be closed. The outer end 5 of each passageway is internally screw-threaded, so as to receive a perforated button or cap 50 to limit the outward movement of said ball valves 49 from said seats 48.

Whenever pressure fluid is introduced into said 10 annular space of said casing string and flows through said passageways 47 and encounters said balls 49 in said open ports 45, the passage of said pressure fluid through said open ports will carry said balls onto their respective seats 48, thereby closing said open ports as well as shutting off said tubing from said annular space. It will be noticed in Figures 6 and 8, that when said balls are seated so as to close said passageways, a portion thereof protrudes into said chamber 44 15 from said seats.

The lower end of said chamber 44 is countersunk (Figures 5 and 6), so as to form an enlarged bore 51 for receiving the upper end of a tubular mandrel 52 which has a sliding fit within said bore 51. It will be noticed that a portion of said mandrel 52 is thickened or upset, so that a shoulder 53 is formed to limit the telescoping of the upper end of said mandrel within said bore. The lower end of said mandrel is internally upset so 20 as to form a shoulder 54 which has a reduced, depending pin 55 for telescoping within a shallow, annular sump or recess 56 in the upper surface of said lower valve body 39. The lower end of said sump 56 is provided with one or more passageways 57 extending through said lower valve body to the lower end thereof, so that a continuous passage is formed from said passageways 47 of said valve cages 46, through said chamber 44, 25 said mandrel 52, said sump 56, said passageway 57 and delivered below said lower valve body 39 and inside of said tubing string 21. The lower surface of said lower valve body is provided with a socket or recess 58, that is internally screw-threaded to receive an externally threaded pin 59 on the upper end of a string of auxiliary or tail pipe 60. It is preferred that this tail pipe extends down within said tubing string to within 30 a short distance of the upper end of said standing valve 25 mounted in the lower end of said tubing.

The upper end of said socket 58 is provided with one or more longitudinally extending passageways 61 extending therefrom to the upper side of said lower valve body 39, so that a continuous passageway is formed from said tail pipe 60, through said socket 58, through said passageway 61, into said sleeve 37 outside of said tubular mandrel 52, through a plurality of longitudinal channels 62 extending through said valve body 34, onto the upper side of said valve 28 and within said tubing 21. It is pointed out that the sump 56 and passageways 57 do not open or connect with the socket 58 and passageways 61. The upper end of said chamber 44 is countersunk and internally screw-threaded to receive an annular box or guide 63 having an axial bore 64 extending therethrough. The lower portion of said bore 64 is counterbored to form an enlarged bore or chamber 65 and a ground, tapered seat 66 is formed on the shoulder between said bore 64 and said chamber 65.

The upper end of said guide 63 is provided with an externally screw-threaded pin 67 for receiving a coupling member 68 having an internal 75

chamber 69 formed therein. This chamber is provided with a plurality of radial ports or openings 70 to provide communication between said chamber and the inside of said tubing. The upper end of said coupling member 68 is provided with an upstanding pin 71, similar to said pin 67, and having a bore 72, similar to said bore 64. This pin 71 is externally screw-threaded for receiving the threaded lower end of an upstanding, elongated tube or protector sleeve 73, that preferably extends co-axially within said tubing 21 and spaced therefrom. The upper end of said sleeve 73 is provided with a plurality of radial ears or lugs 74 for spacing and maintaining the co-axial alignment of said sleeve within said tubing.

It will be noticed in Figures 2, 4 and 6, that the lower portion of an actuating member or weight bar 75 depends within said sleeve 73. Nearly all wells give off a certain amount of free or formation gas from the producing formation which flows up said tubing below said lower valve body 39 and enters said duct 51 and flows therethrough, into said mandrel 52, through said chamber 44 of said valve body 34, into said chamber 69 of said coupling 65, and out through said openings 70 into said tubing above said valve. It is pointed out that this free gas is prevented from accumulating in said tubing below said valve 28 and restricting the inflow of well fluid from said formation. Also, by providing said openings 70 in said chamber 69, said free gas does not enter said protector sleeve 73 nor contact said weight bar 75, nor interfere with the operation thereof.

An elongated, cylindrical dart 76 is mounted in and extends through the lower portion of said sleeve 73, into said bore 72 of said pin 71, through said coupling member 68, into said guide 63, through said chamber 44 and into the upper portion of said tubular mandrel 52. The upper portion of said dart 76 is reduced to form an upstanding, co-axial pin or rod 77 and a flat, annular head 78 is suitably mounted on the upper end of said rod 77, so that the tapered, lower end of said weight bar 75 may readily engage and actuate said rod 77. The lower portion of said dart 76 is provided with an axial bore 79 and the upper end of said bore is provided with a plurality of radial outlet ports 80 extending from said bore to the outer surface of said dart.

As will be seen in Figures 5 and 6, a portion of said dart is externally upset or thickened, so as to form an annular boss or actuating member 81 with a tapered guide surface 82 on its upper edge. It will be noticed in Figures 5 and 6 that the guide surface 82 engages the ball valves 49 upon the upward travel of said dart 76 and gradually forces said balls 49 off their seats 48, until said boss 81 engages and holds said balls in their open position (Figures 5 and 7). Of course, upon the downward travel of said dart, the reverse action takes place and said balls are permitted to gradually engage their seats due to the taper of said guide surface 82. The lower end of said dart is provided with a plurality of spaced, short stops or lugs 84 and a suitable coiled spring 85 is mounted within said tubular mandrel 52. The lower end of said spring rests upon the internal upset portion of said tubular mandrel and the upper end of said spring engages beneath said stops 84, so that at all times said dart is under the tension of said spring 85. The tapered shoulder 86, formed between said lower portion of said dart and said rod 77, en-

gages said seat 66 to limit the upward travel of said dart and to seal off said chamber 44 from said chamber 69 and the tubing above said valve 28.

When said valve 28 has been assembled and made up in said tubing string and said well fluid level has been lowered by the production thereof, as taught in my above-mentioned patents and co-pending applications; said weight bar 75 is suspended on the lower end of a wire line 87 extending up said tubing string 21 and out of said casing head to a suitable control mechanism (not shown). This control mechanism may be of any desired structure, although I prefer to use one of the control mechanisms such as is taught in my above-mentioned patents or co-pending applications. This weight bar will be lowered approximately to the position shown in Figures 2 and 4, which is the opened position of said dart 76 in said valve due to the tension of said coiled spring 85. With said dart in this upper position, said balls 49 will be held off their seats 48 so that said pressure fluid in said casing 20 above said valve 28 will force the well fluid remaining in said casing between the lowermost kick-off valve 26 and said valve 28, through said passageways 47 of said valve cages 46, into said chamber 44, through said tubular mandrel 52, into said sump 56 of said lower valve body 39, through said passageways 57 of said lower valve body and into said tubing 21 below said lower valve body outside of said tail pipe 60. This admitted well fluid will be forced downwardly in said tubing around said tail pipe to the lower end thereof and said pressure fluid from the annular space of said casing will follow this same path of flow. Of course, this well fluid together with the well fluid in said tubing below said valve 28, and the well fluid in said tail pipe 60 and in said valve, will be forced or be displaced upwardly into said tubing above said valve and will lift the well fluid in said tubing. This upward path of flow, which also will be followed by the pressure fluid, is through said tail pipe 60, into said socket 58, through said passageways 61, into said sleeve 37 around said tubular mandrel 52, up through said longitudinal passageways 62 and out on top of said valve 28 in said tubing around said sleeve 13. The pressure fluid from said annular space of said casing, following the same path of flow as outlined for said well fluid, will lift said well fluid up said tubing string to the usual cross T 88 and into the usual flow line 89 where it is led to a separator (not shown), a storage tank (not shown), or any other suitable disposal as desired.

It is pointed out that a perforated band or collar 90 is mounted on said upper valve body 34 between the lower end of said upper connecting collar 29 and the upper end of said sleeve 37, so as to fully cover the outer ends of said threaded ports 45 to protect the same and prevent any extraneous matter entering said passageways 47 of said valve cages 46 and clogging the same, or said perforated cap 50, or causing damage to said balls 49, or some other mechanism of said valve 28. Attention is called to Figures 5, 6 and 8, wherein it will be seen that said upper valve body 34 is formed externally with a shallow, annular channel or recess 91 that extends medially of said body. This channel extends across the open, outer ends of said ports 45 and said caps 50 of said valve cages 46 and underlies the perforated collar 90, so that when fluid flows through the perforations of said collar, 75

said channel 91 will receive the same and lead said fluid to said ports.

When said ball valves 49 are held open by said boss 81 on said dart 76, said tapered shoulder 86 is engaging said seat 66, so that the fluid entering through said passageways 47 of said valve cages 46 will flow down around said dart, as well as into said ports 80, through said bore 79 of said dart, and out the lower end thereof. The pin 71 is provided intermediate its ends with a plurality of elongated, longitudinal, shallow slots or grooves 93. These grooves are so placed on said pin that when said dart 76 is in its upper position (Figures 4 and 5), the lower ends of said grooves are even with or above the upper edge of said pin 67 of said guide 63 and the upper ends of said grooves are below or in the lower portion of said bore 72 of said pin 71. When said dart is in its lower position (Figure 6), the lower ends of said grooves 93 are below said seat 66 on the lower end of said bore 64 and the upper ends of said grooves extend above the upper edge of said bore 64 and into said chamber 69, whereby a passageway is provided from said chamber 65 through said grooves to said chamber 69. This passageway thus formed will prevent the accumulation of free or formation gas in said valve body 34 and in said chamber 65 for two reasons or purposes. First, by venting said gas, said tubing below said valve 28 and said tail pipe 60 may fill with well fluid so that upon the next actuation or opening of said valve 28, a full load or charge of well fluid is obtained; second, to prevent the accumulation of formation gas, which would interfere with the operation of said dart.

In the normal or inoperative position the dart 81 is depressed by the bar 75, so that the pressure fluid closes the valves 49. It is pointed out that the slots 93 are so placed on said stem 71 of said dart 76, as to bleed the free gas from said valve body 34 when said dart is in its lower position. When said dart begins its upward travel to open said ports 45, said slots 93 are closed as soon as their lower ends enter into said bore 64 of said guide 63 and the further escape or bleeding of free gas is terminated. At this point of travel, the balance of said stem 71 between said slots and said shoulder 86 serves as a sliding plug in said bore 64, so that when said balls are pushed open by said guiding surface 82, the pressure fluid entering through the opened ports 45 will assist the spring 85 in lifting said dart 76 to move the same into its upper position, to completely open said ports and seat said shoulder 86 against said seat 66.

With said protector sleeve 73 preventing the upward flowing column of fluid contacting said weight bar 75 or said head 78 on said stem 71, and any free gas being led outside of said sleeve; the operation or the position of said weight bar is not interfered with and a steady, even actuation of said valve 28 is had. If the protector sleeve was not used, the flowing column of fluids would lift said weight bar and give a reciprocating or fluttering action to said stem with the resultant rapid opening and closing of said inlet ports and a faulty operation of said valve 28. When the ports are closed, the free gas escapes up the well tubing and when said ports are open, said free gas will be carried with the well fluid and the pressure fluid down in said tubing below said valve and up said tail or discharge pipe 60 into said tubing above said valve 28. It is

pointed out that in initially kicking off the well, said valve 28 is in its open position, so that all the well fluid in said casing 40 below the lowermost kick-off valve 26 flows or is forced through said valve 28, down into said tubing below said valve and up said tail pipe, as has already been described.

If desired the tubing below said packer may be of a larger diameter than the balance of the tubing string, in order to provide an increased fluid collecting chamber 95. Of course, this chamber will extend down to the standing valve 25 or at least below the lower end of the tail pipe 60. It is preferred to use a formation gas valve 96 in said tubing string 21 above said chamber 95 and below said packer 21. This formation gas release valve 96 may be of any suitable construction, although I prefer to use my own valve such as shown and described in my copending application, Serial No. 317,073, filed February 3, 1940.

Attention is called to the fact that after the well has been kicked off and is being produced, and when said flow valve 28 has been opened, the pressure lifting fluid entering said valve flows therethrough and is introduced into the upper end of said chamber 95 onto the upper surface of said well fluid therein. This well fluid is displaced downwardly in said chamber and up into said tail pipe 60, through said flow valve 28 and into said tubing string around said protector sleeve 13. As additional pressure fluid enters said chamber 95 and builds up the pressure therein, said pressure fluid forcing all well fluid ahead of it will follow the same line of flow as said well fluid. Thus, when said pressure fluid reaches the lower end of said tail pipe 60 to exert its lifting force or action on said well fluid in said tail pipe, this column of well fluid is already flowing due to the above set out displacing action. It will be seen that the lifting force of said pressure fluid is delivered beneath an upwardly moving column of well fluid, whereby there will not be any channelling, cutting, or damaging of said well fluid as there would be if said pressure fluid were introduced down said tail pipe and into said chamber at the lower end of said tail pipe.

In initially kicking off wells where there is a deep submergence of said bottom-hole flow valve 28 in the well fluid, one of my kick-off valves 26 (not shown) may be mounted in said tubing string just above said flow valve; so that when there is too much well liquid in said fluid accumulating chamber 95, in said casing or well bore, and in said annular space of said casing above said packer, the flow valve 28 being normally open will admit well fluid and pressure fluid therethrough to displace well fluid from said chamber into said tubing above said flow valve until the column of well fluid in said tubing, said flow valve and said tail pipe balances the desired operating pressure of pressure lifting fluid. When the pressure within said tubing and said flow valve balances the operating pressure, of course there will be no more flow from said annular space of said casing into said flow valve and the operator at the surface will be unable to unload or kick off the well. However, when it is determined by preliminary survey that such a condition will occur, one of my kick-off valves 26 is mounted in said tubing string just above the upper end of said actuating member 15, so that said actuating member could be picked up when the above-mentioned point of balance has been reached to open this kick-off valve (not shown) to admit pressure fluid at this point in said tub-

ing string. Naturally this kick-off valve will operate and function exactly as my other kick-off valves.

The picking up of said weight bar 15 to open this kick-off valve will admit pressure fluid to cut off the upper portion of the column of well fluid standing in said tubing. The admittance of pressure fluid through this kick-off valve will not only cut off the column of well fluid at this point, but will lift this cut off portion or "slug" up and out of said well, as taught in my above-mentioned patents and co-pending applications, and this lifting will lighten the column of well fluid in said tubing so that additional well fluid may "rock" or flow through said flow valve 28, until a point of balance is reached. The weight bar 15 may again be pulled up into the kick-off valve 26 (not shown) and as soon as the cut off portion or slug of well fluid reaches the surface, said weight bar is again lowered to close said kick-off valve, so that additional well fluid may build up in said tubing above said flow valve 28. This operation may be repeated as often as is necessary until the desired operating pressure can handle the well fluid produced by said producing formation and when this condition occurs, the pressure fluid will flow through said valve into said chamber onto the upper surface of the well fluid in said chamber and lift the same out as has already been outlined above. When the pressure fluid has lifted the well fluid from said chamber and said tail pipe up and out of said tubing, the weight bar 15 has been dropped onto the flat head 18 of said stem 11 (Figure 6) to move said dart 16 downwardly and release the balls 49, so that the pressure fluid entering said passageways 47 will carry said balls onto their seats 48, thereby closing said passageways and terminating the admittance of pressure fluid into said flow valve 28.

In Figures 9 to 14, a slightly modified form of the invention is illustrated which shows how the invention may be made to accommodate two horizontal planes of ports and valve cages therefor. As will be seen from these figures, the structure is substantially the same as that shown in Figures 1 to 8 inclusive. The valve body 128 has been sufficiently lengthened to accommodate the second group or horizontal plane of ball valves 149'. The lower portion of said dart 176 has been elongated to accommodate a second boss or actuating member 181' with a tapered guide surface 182' on its upper edge similar to the boss 181 and guide surface 182 respectively. It will be seen in Figures 9, 12 and 14, that the guide surface 182' is steeper and the inclination thereof is greater than the guide surface 182, so that upon the upward travel of said dart 176, the lower guide surface 182' will engage the lower group of ball valves 149' and open or move the same off their seats 148' before the upper guide surface 182 engages the upper group of ball valves 149 to move the same off their seats 148. The lower end of the slots 193 have already entered the bore 164 above said seat 166 and when this point has been reached (Figure 14), the pressure fluid entering through said lower group of passageways 147' will assist in the further lifting of said dart 176, whereby said lower group of ball valves 149 as well as the upper group of ball valves 149 may be moved to their fully opened positions (Figures 9 and 13).

Upon the downward travel of said dart 176, the reverse action takes place and said balls are permitted to gradually engage their seats the same

as upon the upward travel of said dart and said upper group of ball valves 149 will engage their seats before the lower group of ball valves 149', due to the difference in the tapers of the guide surfaces 182 and 182'. However, while this form of the invention has been described and illustrated with three ports in each group, it is to be understood that each group may contain one or more ports and each group does not have to contain the same number of ports as the other. Neither do the ports have to be in alinement with the corresponding port in the other group, nor is the invention limited to one or two groups as the valve may be constructed with as many groups and as many ports in each group as is desired or required to satisfactorily handle the production problem presented on each installation.

The difference in the tapers of the guide surfaces 182 and 182' serve two purposes: first, by opening one group of ball valves ahead of the other group, the spring 185 does not need to be as strong as would be required if both groups were opened simultaneously; second, the pressure fluid entering through the lower passageways 147', engaging beneath the boss 181, will assist in the lifting of said dart due to the sliding action or function of said stem 177 below the lower ends of said slots 193, so that this first admitted pressure fluid lends assistance to the action of said spring 185.

It is pointed out that various changes and modifications of the invention may be made as is necessary to accommodate the numerous and various producing conditions presented without departing from the spirit of the invention.

What I claim and desire to secure by Letters Patent is:

1. A valve for a well fluid lifting apparatus having a well tubing in a well casing including, an upright enclosure adapted to be connected in the tubing and having a passage therethrough and a fluid outlet, a valve seat below said outlet opening from the passage at the upper end thereof, an inlet valve in the enclosure below said seat communicating with said passage for admitting fluid from the casing into the tubing, and spring actuated means having a valve member engaging said seat for controlling the flow of fluid through said outlet and said means also engaging said inlet valve to hold it open.

2. A valve for a well fluid lifting apparatus having a well tubing in a well casing including, an upright enclosure adapted to be connected in the tubing and having a passage therethrough and a fluid outlet, a valve seat below said outlet opening from the passage at the upper end thereof, an inlet valve in the enclosure below said seat communicating with said passage for admitting fluid from the casing into the tubing, spring actuated means having a valve member engaging said seat for controlling the flow of fluid through said outlet and said means also engaging said inlet valve to hold it open, and means operable from the surface of the well for depressing said spring actuated means to unseat said valve member from said seat and to release the inlet valve.

3. A valve for a well fluid lifting apparatus including, an upright enclosure having a fluid passage therein, an inlet valve for admitting lifting fluid to said passage, spring actuated means engaging said inlet valve and holding it open, and means operable from the surface of

the well for depressing said spring actuated means to release said inlet valve.

4. In a well fluid lifting system the combination of, an eduction pipe, a packer disposed around said pipe, a well liquid discharge pipe communicating with the eduction pipe having its inlet a substantial distance below the packer to receive a column of well liquids, flow means having a lifting fluid inlet disposed above said packer and a conductor for conveying the admitted fluid below said packer for displacing the well liquids downwardly around said discharge pipe to its inlet, whereby the well liquids are expelled through the discharge pipe into the eduction pipe through which it is lifted to the well surface, means having a connection with the lifting fluid inlet for holding said inlet open, and surface operated means for disengaging the holding means from said lifting fluid inlet to permit the pressure lifting fluid to close said inlet.

5. In a well fluid lifting system the combination of, an eduction pipe, a packer disposed around said pipe, a well fluid discharge pipe communicating with the eduction pipe having its inlet a substantial distance below the packer to provide a column of well liquids, flow means having a lifting fluid inlet disposed above said packer and a conductor for conveying the admitted fluid below said packer for displacing the well liquids, whereby said well liquids are discharged through said eduction pipe, resilient means for maintaining the inlet open, and surface controlled means for releasing said maintaining means, whereby the pressure lifting fluid shuts itself off.

6. In a well fluid lifting system the combination of, an eduction pipe, a packer disposed around said pipe, a well fluid discharge pipe communicating with the eduction pipe having its inlet a substantial distance below the packer to receive a column of well liquids, flow means having a lifting fluid inlet disposed above said packer and directing the admitted fluid below said packer for displacing the well liquids downwardly around said discharge pipe to its inlet, whereby the well liquids are expelled through said discharge pipe into the eduction pipe through which it is lifted to the well surface, means having a connection with the lifting fluid inlet for holding said inlet open, surface operated means for disengaging the holding means from said lifting fluid inlet to permit the pressure lifting fluid to close said inlet, the column of well liquids accumulating in said discharge pipe while said inlet is closed, and means for venting any free gas while the liquids are accumulating and said inlet is closed.

7. In a well fluid flowing device having a well tubing suspended in a well casing including, an elongate body having connecting collars on each end thereof for connecting said body in the well tubing, an axial bore extending through said body so as to form a pasageway with said well tubing, a radial port in the upper portion of said body, a valve for said port adapted to be operated from the bore of said body, operating means movable in said bore for operating said valve, an elongated actuating member separate from said operating means depending in said well tubing for actuating said operating means, and a wire line depending in said well tubing for suspending said actuating member and controlling the operation of the same.

8. In a well fluid flowing device having a well tubing suspended in a well casing including, an

elongate body having connecting collars on each end thereof for connecting said body in the well tubing, an axial bore extending through said body so as to form a passageway with said well tubing, a radial port in the upper portion of said body, a valve for said port adapted to be operated from the bore of said body, a second port in said body, a valve for said second port adapted to be operated from the bore of said body, operating means mounted in said bore for operating said valves, an elongated actuating member separate from said operating means depending in said well tubing for operating said operating means, and a wire line depending in said well tubing for suspending said actuating member and controlling the operation of the same.

9. As a subcombination in a well flowing apparatus, a valve including a valve body having a bore extending therethrough and a flow channel extending therethrough separately from said bore for conveying fluids, an inlet port extending laterally to said bore, said inlet port having internal screw-threads for receiving a valve cage, the upper end of the bore being screw-threaded, and a removable seat screwed into the upper end of said bore.

10. As a subcombination in a well flowing apparatus, a fluid inlet valve, an actuating dart for the fluid inlet valve including, a dart body, the major portion of said body being tubular and having an opening whereby fluid may enter said body and flow therethrough to facilitate the flow of fluid by and below said dart body, an upset actuating portion on said body for actuating the fluid inlet valve, a supporting guide on the lower portion of said body, a resilient member engaging said guide, an actuating stem extending from the upper portion of said body, and an actuating member to engage and operate said dart for moving the same.

11. As a subcombination in a well flowing apparatus, a fluid inlet having a bore therein, an actuating dart for the fluid inlet valve in said bore and including, a dart body, the major portion of said body being tubular and having an opening whereby fluid may enter said body and flow therethrough to facilitate the flow of fluid by said dart body, an upset actuating portion on said body for actuating the fluid inlet valve, a supporting guide on the lower portion of said body, a resilient member engaging said guide, an actuating stem extending from the upper portion of said body, and an actuating member to engage and operate said dart for moving the same, a seat in said bore for providing a vent for free well gas and an annular valve member on the upper portion of said body adjacent said stem for engaging the seat for controlling the venting of free gas from the well fluid.

12. As a subcombination in a well flowing apparatus, a fluid inlet valve, an actuating dart for the fluid inlet valve including, a dart body, the major portion of said body being tubular and having an opening whereby fluid may enter said body and flow therethrough to facilitate the flow of fluid by said dart body, an upset actuating portion on said body for actuating the fluid inlet valve, a supporting guide on the lower portion of said body, a resilient member engaging said guide, an actuating stem extending from the upper portion of said body, and an actuating member to engage and operate said dart for moving the same, a seat in said bore for providing a vent for free well gas and an annular valve member on the upper portion of said body ad-

5 jacent said stem for engaging the seat for controlling the venting of free gas from the well fluid, an elongated slot formed in said stem so that when said dart is in its inoperative position any free gas may be vented therethrough.

13. In a well flowing apparatus, a valve including, a valve body having a bore extending therethrough and a flow channel extending therethrough separately from said bore, an inlet port extending laterally to said bore, said inlet port having internal screw-threads for receiving a valve cage, a well fluid delivery pipe connected to the lower end of said valve, a conductor connected to the lower portion of said bore for conveying a lifting fluid from said port below said valve outside of the well fluid delivery pipe, and means whereby the lifting fluid will displace the well fluid through the well fluid delivery pipe, the well fluid delivery pipe being so connected to said valve that the well fluid expelled from the well fluid delivery pipe flows outside and around said lifting fluid conductor and through the flow channel.

14. A flow valve for a well fluid lifting system having a well flow pipe including, a body adapted to be connected into the flow pipe and having a bore and flow channels extending therethrough separately from said bore for providing a passage for fluid from below the body into the well flow pipe, an inlet port in said body connected to the bore, a closure member for said port, means mounted in said bore for actuating said closure member, and means at the upper portion of the actuating means for venting any free gas while the well fluid is accumulating in the flow pipe.

15. In a well flowing apparatus the combination of, an elongate structure having a passage therethrough for connecting at its upper end with the usual well tubing, a well fluid accumulating chamber connected with the lower end of said passage, a normally open pressure fluid inlet valve opening to said passage and having an actuating element exposed in said passage, a seat in the passage and located above said valve for venting free gas therethrough, and an elongate operating member engaging the valve actuating element movable in the passage of said structure and having means for engaging the seat to shut off the passage to control the flow of free gas, a conduit extending from the accumulating chamber for conveying and discharging fluid into the passage above the seat when the actuating element is engaged with the seat.

16. A well flowing apparatus having a well tubing in a well casing including, a valve body in said tubing and having a bore therethrough, a flow passage in said body for conveying fluids into said tubing above said body, an inlet valve in said body for admitting fluid into said bore, a weight bar movable in said tubing for controlling the operation of the inlet valve, in combination with a shield mounted on the valve body and into which said bar telescopes, whereby said bar is protected against upward displacement by the upwardly flowing fluids in said tubing.

17. A well flowing apparatus having a well tubing in a well casing including, a valve body in said tubing, a flow passage in said body for conveying fluids into said tubing above said body, an inlet valve in said body, a weight bar movable in said tubing for controlling the operation of the inlet valve, said inlet valve including, a bore extending through the valve body, an inlet port extending laterally to said bore for admitting fluid into said bore, a closure mem-

ber for said port projecting into said bore for controlling the admittance of fluid into said bore, and an actuating dart in said bore for engaging the projecting portion of said closure member, the upper portion of said dart extending above said valve body to be engaged and operated by said weight bar.

18. A well flowing apparatus having a well tubing in a well casing and an inlet valve mounted in the tubing and a weight bar movable in said tubing for controlling the operation of the inlet valve, said inlet valve including, a valve body having a bore extending therethrough, an inlet port extending laterally to said bore for admitting fluid into said bore, a closure member for said port projecting into said bore for controlling the admittance of fluid into said bore, an actuating dart in said bore for engaging the projecting portion of said closure member, the upper portion of said dart extending above said valve body to be engaged and operated by said weight bar, and a spring supporting said dart.

19. A well flowing apparatus having a well tubing in a well casing and an inlet valve mounted in the tubing and a weight bar movable in said tubing for controlling the operation of the inlet valve, said inlet valve including, a valve body having a bore extending therethrough, an inlet port extending laterally to said bore for admitting fluid into said bore, a closure member for said port projecting into said bore for controlling the admittance of fluid into said bore, an actuating dart in said bore for engaging the projecting portion of said closure member, the upper portion of said dart extending above said

5 valve body to be engaged and operated by said weight bar, and means at the upper portion of said bore for venting any free gas into said tubing while the well liquids are accumulating in said tubing and said inlet is closed.

20. A well flowing apparatus having a well tubing in a well casing and an inlet valve mounted in the tubing and a weight bar movable in said tubing for controlling the operation of the inlet valve, said inlet valve including, a valve body having a bore extending therethrough, an inlet port extending laterally to said bore for admitting fluid into said bore, a closure member for said bore projecting into said bore for controlling the admittance of fluid into said bore, an actuating dart in said bore for engaging the projecting portion of said closure member, the upper portion of said dart adapted to be engaged and operated by said weight bar, a portion of 10 15 20 said dart being tubular to assist in the flow of fluid through said bore of said valve body.

21. A flow valve for a well fluid lifting system having a well flow pipe in a well casing including, a body adapted to be connected in the flow pipe and having a bore and flow channels extending therethrough, said flow channels conveying fluid through the body separately from the bore and into the flow pipe, a radially extending inlet port in said body connected to the bore for admitting fluid into said bore from said casing to displace well fluid to flow through said channels, a closure member for said port, and surface controlled means mounted in said bore for actuating said closure member.

JEDDY D. NIXON.
